UNITED STATES PATENT OFFICE

GEORGE WALTER DUNNICKAN, OF BLOOMFIELD, NEW JERSEY, ASSIGNOR TO DOROTHY GRAY, INC., A CORPORATION OF NEW JERSEY

VANITY CASE

Application filed July 16, 1929. Serial No. 378,793.

The invention relates to vanity cases and has as an object, the provision of a vanity case having a self opening cover adapted in the opening movement to feed powder to a removable powder puff housed in the case.

5 It is a further object of the invention to provide a vanity case having a powder compartment with a readily removable closure for filling purposes.

10 It is a further object of the invention to provide a vanity case having a novel form of powder feed to a powder puff chamber.

15 It is a further object of the invention to improve generally upon the physical structure of devices of this type.

20 Further objects of the invention will appear from the following description when read in connection with the accompanying drawings, showing an illustrative embodiment of the invention, and wherein:

Figure 1 is a perspective view.

Fig. 2 is a plan view with the cover open and in section and with a portion of the wall broken away.

25 Fig. 3 is a vertical section on line 3—3 of Fig. 2 with the cover closed.

Fig. 4 is a horizontal section on line 4—4 of Fig. 3 and

30 Fig. 5 is a vertical section on line 5—5 of Fig. 2.

As shown, the device comprises an outer frame member 10 having sides 11 overlapping an inner frame member which is channel-shaped in cross section, having vertical sides 12, 13, 14, 15, telescoping within the sides 11 of the member 10, and inner members 16, 17, 18, 19, forming the enclosure of the powder chamber 20, the vertically extending members 12, 13, 14, 15, being connected to the members 16, 17, 18, 19, by a horizontal portion 21 which forms a portion of the exterior of the box at its bottom.

To close the powder chamber 20, there is shown a plate 22 having an opening 23 in its central portion, and the margins of the plate provided with portions 24, 25, 26, 27, which are mitered at their corners and folded upwardly and inwardly in spaced relation to the body of the plate 22, the edges of the members 24—27, being turned into a spring re-

ceiving seat 28 to engage the lower coil of a helical spring 29. The plate 22 with its assembly of spring 29 is adapted to fit within the lower opening of the chamber 20. To hold the assembly in place there is shown a disk 30 overlying the plate 22 and underlying the members 24—27, and projecting through slots 31—32 in the members 24 and 26 and through slots 33, 34, in the members 16, 17. Disk 30 is shown as having a depressed portion 35 upwardly concave in contour, the edges of the depressing portion projecting into the opening 23 of plate 22 and a rib 36 is provided in the concavity for engagement by the fingers of the user.

The chamber 20 may be opened by grasping the rib 36 and revolving the disk 30, causing the projections 37, 38 thereof to leave the slots 33, 34, when the plate 22 may be freely removed, carrying with it the spring 29 and the powder supporting diaphragm 39, when the box may be inverted and the chamber supplied with powder.

To preserve the spacing of the members 25, 27, filler plates 40, 41 are shown in the angle 75 of the turned over members 25, 27.

To support the cover 42 of the box, the walls 11 are shown as provided with outer rim members 43, 44, the rim member 43 being depressed as indicated at 45 to provide a horizontal depressed member 46 upon which the free edge of the cover 42 may seat, and the remaining opposite sides of the box as shown in Fig. 5 have their upper edges turned inwardly as at 47, 48, then downwardly as at 49, 50, terminating in spaced relation to the members 18, 19. The member 46 also has its edge turned downwardly as at 51, terminating in spaced relation to the upper edge of the member 17. The members 49, 50 are provided at their rear ends with openings to receive the hinge pintle 52 upon which the cover 42 swings.

To cause the hinge to fly open when released, there is shown a torsion spring 53 coiled about the pintle 52 and having its ends anchored in the members 49, 50, the center of this spring being formed into a bail-like member 54 adapted to press upwardly upon the lower surface of the cover 42.

To hold the cover in closed position, there is shown a catch 55 engaging a notch in the cover 42, the catch being resilient and having ears 56, 57 riveted to the member 45 as clearly shown in Fig. 2; a button 58 projecting through the box by which the catch may be actuated to withdraw the same from the notch to allow the cover to spring open under action of spring 53. Desirably a mirror 59 is provided, carried by the lower surface of the cover 42.

To feed powder from the chamber 20 to a powder puff 60, there is shown a sliding perforated diaphragm 61 reciprocable in the slots provided between the upper edges of the members 16—19 and the members 49, 50, 51, the diaphragm being held in normal position by means of a leaf spring 62. The powder puff 60 rests or is supported directly on the diaphragm 61 and incidental to forward reciprocation or powder-feeding movement thereof the puff abuts the wall 51 whereby undue movement of the puff is avoided. The openings in the diaphragm 61 are shown as formed by striking portions 63 of the diaphragm downwardly therefrom. When the cover of the box is released and flies open, the portion 64 of the cover projecting beyond the hinge will move downwardly and impinge against the edge 65 of the diaphragm 61, causing movement thereof against the resistance of the spring 62 and the downwardly struck portions 63 being directed as shown, powder in the chamber 20 pressed upwardly against the diaphragm by the plate 39 will be fed through the openings and upon the puff 60.

There is thus provided a very convenient and efficient form of vanity box which will feed powder to the compact by the act of opening the box and wherein the powder may be readily renewed when exhausted.

Minor changes may be made in the physical embodiment of the invention without departing from the spirit thereof within the scope of the appended claims.

I claim:

1. A vanity box comprising, in combination, a casing having a powder chamber and a powder puff chamber therein, a perforated reciprocable diaphragm separating said chambers and arranged to directly support a puff, a cover for said puff chamber, and means operated by movement of said cover to cause movement of said diaphragm to feed powder to and rub the same over the surface of said puff.

2. A vanity box comprising, in combination, a casing having a powder chamber and a powder puff chamber therein, a perforated reciprocable diaphragm separating said chambers, a cover for said puff chamber hinged upon said casing, a portion of said cover extending rearwardly from the hinge and entering the casing as the cover opens, a

portion of said diaphragm extending into the path of movement of said cover portion for abutment thereby to cause movement of the diaphragm to feed power to a powder puff in the puff chamber.

3. A vanity box comprising, in combination, a casing comprising outer walls and an inner wall spaced therefrom at the end of one dimension of the casing, said casing having a powder and a powder puff chamber closed at one side by said inner wall, a reciprocable perforated diaphragm separating said chambers and projecting into said space, said diaphragm being arranged to directly support a powder puff, a cover hinged to said casing having a portion extending outwardly beyond the hinge axis and movable into said space and into contact with a portion of said diaphragm and thereby move the latter when the cover opens.

4. A vanity box comprising, in combination, a casing comprising outer walls and an inner wall spaced therefrom at the end of one dimension of the casing, said casing having a powder and a powder puff chamber closed at one side by said inner wall, a reciprocable perforated diaphragm arranged to directly support a powder puff, said diaphragm separating said chambers and projecting into said space, a spring resiliently holding said diaphragm in normal position, a cover hinged to said casing and having a portion extending rearwardly of said hinge and dipping into said space into contact with said diaphragm when the cover opens, a spring to open said cover when released and a catch to hold said cover closed against the action of said spring.

5. A vanity box comprising, in combination, a casing having a powder puff chamber and a powder chamber therein, a perforated reciprocable diaphragm arranged to directly support a powder puff, said diaphragm separating said chambers, resilient means to hold said diaphragm in normal position, powder deflecting means carried by said diaphragm adjacent perforations therein projecting into said powder chamber and angularly in the direction of reciprocation of said diaphragm away from normal position, means in the powder chamber to press the contents thereof against said diaphragm and into the path of movement of said deflecting means, a cover for the puff chamber and means whereby opening movement of said cover causes reciprocation from normal position of said diaphragm.

6. A vanity case comprising a casing formed with external walls forming the edges thereof, internal walls parallel with and spaced from said external walls and defining a powder chamber, said internal walls of less height than said external walls, a sliding perforated diaphragm supported on the inner edges of said internal walls and

separating said powder chamber from a powder puff chamber, means overlying said diaphragm to guide its movement and forming a portion of the puff chamber enclosure, a cover for said puff chamber hinged upon the casing, a projection upon said cover extending beyond the hinge acting upon an edge of said diaphragm in one of the spaces between said walls to cause movement of said diaphragm when the cover is opened, a cover for said powder chamber, a plate for pressing powder toward said diaphragm and a spring abutting said last named cover to move said plate.
